ADJUSTABLE WAVE GUIDE SUPPORT TEST STAND

Paul C. Ely, Jr., and Robert J. McCaw, Clearwater, Fla.,
assignors to Sperry Rand Corporation, Great Neck,
N.Y., a corporation of Delaware

Filed Mar. 16, 1962, Ser. No. 69,298

Term of patent 14 years

(CL D52—6)

FIG.1.

FIG.2.

FIG.3.

FIG.4.

FIG. 1 is a front elevational view of an adjustable wave guide support test stand showing our new design;

FIG. 2 is a top plan view of FIG. 1;

FIG. 3 is a side elevational view taken from the right side of FIG. 1; and

FIG. 4 is a side elevational view taken from the left side of FIG. 1.

The rear of the test stand is substantially a mirror image of the front shown in FIG. 1.

We claim:

The ornamental design for an adjustable wave guide support test stand, as shown and described.
